UNITED STATES PATENT OFFICE.

JOHN W. POWELL, OF WELCH, WEST VIRGINIA.

LOADING CONVEYER.

Application filed May 12, 1926. Serial No. 108,607.

This invention relates to a conveyer for conveying "muck," loose coal and the like from a pile where it has been blown or knocked down in a mine, the general object 5 of the invention being to provide means for placing a conveyer in such a position that the material will drop upon the same when it is blown or knocked down from the mine face, so that when the conveyer is started up, 10 it will remove the loose material to a point of discharge.

Another object of the invention is to provide the conveyer with a nose or plow which is arranged at one side thereof so that the 15 conveyer can be forced under a pile of material without damage to the conveyer part.

A further object of the invention is to provide power driven means for moving the conveyer, or a portion thereof, trans- 20 versely under a pile of material or to a position where the material will fall when knocked down.

This invention also consists in certain other features of construction and in the 25 combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:

35 Figure 1 is a plan view showing the device in use in a mine.

Figure 2 is an elevation of Figure 1.

Figure 3 is a section on line 3-3 of Figure 2.

40 Figure 4 is a section on line 4-4 of Figure 3.

In these views, A indicates a sectional conveyer which is composed of the horizontal I-beam 1 and the endless member 2 which 45 passes over the I-beam and has the flights 3 secured thereto, the endless member passing over suitable pulleys journaled in the I-beam, one of which is connected by the gears 4 and 4' and shaft 5 with the shaft of a 50 motor 6 so that the movable part of the conveyer is operated from said motor. One part of the endless member passes over the I-beam and the other portion under the I-beam. The conveyer is carried by a horizontal platform 7 to the outer edge of which a vertically disposed beam 8 is secured, the

platform and beam being formed with each section. The platform extends beyond the inner edge of the conveyer and a plate 9 is connected with the extended edge of said platform and slopes upwardly at an angle and is supported by the top edge of the inner flange of the beam 1. This plate and the extended part of the platform forms a shoe or plow which enables the device to be 60 moved transversely under a pile of material, the plate 9 protecting the edge of the conveyer from the material.

A plurality of stub axles 10 have their bases 11 bolted to the beam 8 and drums 12 are rotatably supported by said axles. A cap 13 is bolted to each drum and a screw shaft 14 is pivoted to each cap. A nut member 15 engages each shaft and said member is pivoted in a block 16 to which the forked lower end of an upright 17 is pivoted. Each upright is provided with a threaded socket to receive a threaded shaft 18 which has its outer end pointed and a point 16' is formed on the base of each block 16. Thus the blocks 16 can be clamped to the mine floor by turning the shaft 18 in the upright 17 to cause its pointed end to engage the roof of the mine, while the block engages the floor.

85 A pair of cables 18' engage the drums 12 and are connected with the drums or winches 19 which are geared to the shaft of motor 20, so that the drums can be rotated in either direction from the motor. As will be seen, 90 when the drums are turned, the shafts turn in the nut members 15 and thus said shafts will be moved longitudinally and they will carry with them the drums, the conveyer support and the conveyer. Thus the conveyer can be forced under a pile of material or it can be moved transversely against the mine face so that the material knocked from the face will fall upon the conveyer. Then by starting up the motor 6, the material will be fed by the conveyer from the pile on to a second conveyer B which will 95 convey it to a point of discharge.

100 The various sections may be connected together as shown at 21 and each cap 13 may be provided with a hole 22 for receiving a cross-bar or the like so that the parts can be turned without using the motor.

105 The beam 8 should be sufficiently high to prevent the material dropping over the same upon the drums and the plate 9 must extend over the conveyer a sufficient distance

to protect the parts thereof from the material when the device is being forced under a pile of material.

As will be seen, this device will enable 5 loose coal, muck and the like to be easily and quickly removed from the face of the mine from which it is blown or knocked down and without the use of manual labor. By making the parts in sections, they can 10 be adjusted easily against the mine face.

It is thought from the foregoing description that the advantages and novel features of my invention will be readily apparent.

I desire it to be understood that I may 15 make changes in the construction and in the combination and arrangement of the several parts, provided that such changes fall within the scope of the appended claim.

What I claim is:—

20 An apparatus of the class described,

comprising a platform having a vertical part at one edge, a shoe or plow at the other edge, a conveyer on the platform between the vertical part and the plow, stub axles connected with the vertical part, a drum on each 25 axle, a cap connected with each drum, a screw shaft connected with each cap, a nut member on each shaft, a block in which the nut member is pivoted, an upright having a forked lower end pivoted to the block and 30 having a threaded socket in its upper end, a threaded shaft engaging the socket and having a pointed end engaging the roof of a mine, cables engaging the drums, winches 35 on the platform and to which the cables are fastened and a motor for driving the winches.

In testimony whereof I, affix my signature.

JOHN W. POWELL.
